DIGESTIVE APPARATUS

Filed Dec. 8, 1928

UNITED STATES PATENT OFFICE

PHILIP A. GOLDFISCH, OF KANSAS CITY, MISSOURI

DIGESTIVE APPARATUS

Application filed December 8, 1928. Serial No. 324,790.

This invention relates to digestive apparatus used in carrying out the Kjeldahl process, and has for its principal object the provision of ejector for the fume tube which will 5 eliminate all back flow of fluids into the fume tube when the device is in operation.

A further object of this invention is the provision of a digestion apparatus having an ejector for the fume tube with a plurality of 10 stages of ejection, said ejector being integral with said flame.

Further objects of the present invention are simplicity and economy of construction, and uniformity and reliability of operation.

With these general objects in view as well as minor objects which will appear during the course of the detailed specification, reference will now be made to the accompanying drawings in which:

20 Figure 1 is a side elevation of a digestive apparatus, partly broken away, embodying this invention;

Fig. 2 is a sectional view taken on line II—II of Fig. 1, with parts broken away;

25 Fig. 3 is an enlarged section taken on line III—III of Fig. 2;

Fig. 4 is a fragmentary section taken on line IV—IV of Fig. 3;

Fig. 5 is a horizontal section taken on line 30 V—V of Fig. 3; and

Fig. 6 is a modified form showing but a single stage of ejection.

Like reference characters designate similar parts throughout the several views and numeral 35 10 designates a suitable support for the fume tube and ejector apparatus; 11 is a fume tube of a digestive apparatus provided with nozzle 12 by means of which the flasks (not shown) are connected. The digestion

40 apparatus is of that type in which vapors are released in the fume tube and drawn therefrom by means of a ventilation system. Fume tube 11 is preferably disposed in a horizontal position and is integral with and in

45 direct communication with a vertically dis-

posed ejector 13 having a vertical stack 14 extending therefrom.

A blower 15, driven by any suitable motor M, is in communication with the ejector 13 through a tube 16. Tube 16 is in direct connection with the restricted nozzle 17 which increases the velocity of the air delivered from said blower as it passes therethrough and is provided with a drain pipe 16'. Nozzle 17 projects into an upwardly converging tube 18 which terminates in a nozzle 19, slightly greater in cross sectional area than nozzle 17, that in turn extends into another upwardly converging tube 20 with a restricted opening 21' slightly greater in cross sectional area than nozzle 19 and having an outward flange 21 which meets the outer wall of the ejector B. The tubes 18 and 20 are spaced apart from the wall of ejector 13 to form a chamber 22 into which the vapors from the fume tube 11 is drawn by the suction action of the ejector as hereinafter described. A series of openings 23 are formed in the tube 18 adjacent the upper end of nozzle 17. It has been found advantageous to have some of the openings 23 extend slightly above the nozzle 17 to facilitate proper circulation. The lower portion of tube 18 is provided with drain openings 24 which permit the condensed vapor to pass into the chamber 22 to be carried therefrom by means of a drain tube 25 which communicates with said chamber below the fume tube 11. The tube 20 is also provided with a series of openings 26 which communicate with chamber 22 through which vapors from said chamber pass when the device is in operation.

Drain openings 27 are also formed adjacent the bottom of tube 20 for the drain of liquid therefrom. It is apparent that when properly proportioned any desired number of stages of ejection may be used.

The construction as shown in Fig. 6 provides for but one stage of ejection with the tube 28 provided with a nozzle 29 and having

a flange 30 which meets the side wall of the ejector 13. Otherwise the construction is the same as that shown and described in the preferred form.

5 In the operation of this device the heated vapors in the fume tube 11 are drawn therefrom into chamber 22 through openings 23 and 26 by the suction created by air from the blower being forced at a high rate of speed 10 through the nozzles 17 and 19 and then through the restricted portion 21' of tube 20 and into the slack 14 where it passes to the atmosphere. The air at room temperature and at a high velocity coming in contact with the

15 vapors from the fume tube gives partial condensation of the vapor in the ejector and throughout the length of the stack, thus diminishing to a large extent, the escape of strong vapors into the air.

20 The restricted opening 20' of the top tubes 20 is sufficiently large to permit the proper flow of air and vapor, but is too small to permit any back flow of gases from the flue into the ejector and fume tube which would 25 greatly retard the action of the device, and since tube 20 is flared at its top to completely close the flue from the chamber 22 except through tube 20, no gases can escape back into the fume tube.

30 What I claim is:

1. In a digestive apparatus of the class described, a fume tube, a stack, an ejector having a housing connecting said fume tube with said stack, a series of nozzles housed in said ejector housing and having openings formed through the walls thereof, means for forcing a fluid through said nozzles to draw fluids from said fume tube through said openings into said nozzles, and a restricted nozzle at the mouth of said ejector through which all of the fluid forced from the fume tube to the stack must pass, and means for draining liquid from said ejector.

45 2. In a digestive apparatus of the class described a fume tube, a stack, an ejector having a housing connecting said fume to said stack, a series of cooperating conical shaped nozzles positioned within said housing and spaced apart from the inner walls thereof to form an outer chamber, each of said nozzles having its discharge end restricted and extended into the next adjacent nozzle respectively, openings formed in the wall of said nozzles in transverse alignment with the end

50 of its respective inserted nozzle, drain openings formed through the wall at the lower extremity of each of said nozzles whereby liquid from said nozzles is drained into said outer chamber and a tube communicating

55 with said outer chamber whereby liquid is drained therefrom and an outturned flange integral with the top nozzle of said series adapted to engage the outer wall of the ejector to completely close the space between the

60 nozzle and the housing of the ejector.

3. In a digestive apparatus of the character described, a fume tube; a stack, an ejector having an outer chamber; an axially disposed, upwardly converging tube positioned in said ejector and having an outwardly extending flange, at its upper end adapted to engage the wall of said ejector; openings formed through the wall of said tube intermediate its ends; and a nozzle extending into the lower portion of said tube with its upper end in a horizontal plane passing through the openings formed in said tube.

In testimony whereof I hereunto affix my signature.

PHILIP A. GOLDFISCH.
